VELOCIPEDE

Raymond Boucher, Dothan, Ala.

Filed Oct. 22, 1963, Ser. No. 77,085

Term of patent 7 years

(Cl. D34—15)

FIG. 1

FIG. 2

FIG. 3

FIG. 4

FIG. 1 is a side view in perspective of a velocipede embodying my new design;

FIG. 2 is a perspective view from above of the velocipede of FIG. 1;

FIG. 3 is a side view in perspective of the velocipede of FIG. 1 showing the side opposite that shown in FIG. 1; and

FIG. 4 is a rear elevational view of the velocipede of FIG. 1.

The dominant features of my design reside in the portions shown in full lines.

Portions of the broken lines have been omitted in FIGURES 1, 2 and 3 for convenience of illustration.

I claim:

The ornamental design for a velocipede, substantially as shown and described.
